UNITED STATES PATENT OFFICE.

PAUL HOFFMAN, OF LA GRANGE, ILLINOIS, ASSIGNOR TO RAMAPO AJAX CORPORATION, OF NEW YORK, N. Y., A CORPORATION OF NEW YORK.

SWITCH-ACTUATING MECHANISM.

Application filed March 12, 1926. Serial No. 94,158.

This invention relates to improvements in switch actuating mechanism, and especially to improvements in the means for adjusting the throw of the switch points and for imparting a straight line motion to the switch bar.

The invention relates particularly to a switch stand in which the switch bar moves in a straight line in effecting the throwing of the switch points, and thereby provides more certainty and security of action. The invention also consists in a construction which permits an adjustment of the throw of one of the switch points with relation to the other without in any manner affecting the throw of the latter and thereby permitting more flexibility in installation and more rapid and accurate adjustment than heretofore. These features of my invention are obtained without sacrificing strength or ruggedness of construction, and said construction also permits all of the principal operating parts to be enclosed within the base of the stand where they are protected from injury by accident or by the elements. The construction is simple and compact, the actuating mechanism is positive in its action, and the device comprises relatively few parts that are easy and economical to manufacture and assemble.

Various other objects and advantages of the invention will be obvious from the following particular description of one form of mechanism embodying my invention or from an inspection of the accompanying drawings; also the invention consists in certain new and novel features of construction and combinations of parts hereinafter set forth and claimed.

40 In the accompanying drawings:

Fig. 1 is a front elevation of the switch stand with the lower portion of the outer casing broken away to show the operating parts therein;

45 Fig. 2 is a view looking downwardly on the base portion from line 2-2 of Fig. 1;

Fig. 3 is a side elevation of the upper portion of the switch stand;

50 Fig. 4 is a side elevation of the switch stand mounted on extensions of the track ties; and

Fig. 5 is a detail of a portion of the adjusting mechanism.

55 The drawings which form part of this specification show the usual switch stand

features of a casing A, target B, handle C, crank shaft D and crank E, the whole being mounted on any suitable supports such as extensions of the track ties which carry the track rails and switch points.

60 Adjusting mechanism for the switch points is enclosed within the base F of casing A, where it is protected from injury by accident or by the elements, and yet is readily accessible by removal of covers G. 65 The lower edges of the end walls 10 of base F are provided with oppositely disposed notches 11 and 12 which extend upwardly sufficiently to permit a switch bar to slide therethrough over pipe rollers 13 journalled 70 in the side walls of the base F.

The bar 14 is preferably formed as a long and narrow member of dimensions sufficient to give it necessary strength and rigidity and yet to permit a free sliding movement 75 through the wall notches 11 and 12.

Projecting upwardly from the upper surface of the bar and intermediate the ends thereof are two lugs 15 and 16 similar in construction.

80 As shown, the lug 15 is formed of two pieces of angle iron placed back to back and providing a base portion fitting in a depression 18 formed in the upper surface of bar 14. Plate 17 is attached to bar 14 by 85 rivets or by any other suitable attaching means. Similarly, lug 16 is secured to plate 19 which is fitted in a depression 20 in bar 14 and secured thereto by rivets. Each of lugs 15 and 16 may, however, be 90 formed as an integral member or in any other desired manner, and be secured to bar 14 in any suitable manner or may be integral therewith.

Lug 15 has a smooth opening therethrough 95 to receive a threaded spacing rod member 21, and similarly lug 16 has a smooth opening to receive a threaded spacing rod 22.

These spacing rods 21 and 22 are similar in construction, formed with head portions 100 23 and 24 respectively, having flat smooth surfaces 25 and 26 facing each other to engage alternately with the crank E.

As shown at 27 in Fig. 2 each head extends a greater distance on one side of 105 switch bar 14 than on the other side, providing an extensive contact surface for crank E.

110 As shown in detail in Fig. 5 the head 23 has lugs 29 projecting from one side edge,

to straddle the switch bar 14. The portion 30 of the head's edge between lugs 29 slides along the upper surface of the bar 14 while the lugs 29 are so spaced that their 5 inner surfaces will slidingly engage the edges of the bar 14 when the rod 21 is moved through the lug 15 to change the adjustment of the head 23. The spacing rod 21 is held securely in adjusted position by 10 means of lock nuts 31 and 32 which may be tightened up to engage opposite sides of lugs 15 and 16.

In operation, the switch points are thrown by moving the crank E from one extreme 15 position engaging one head to the other extreme position engaging the other head.

It is obvious that if when the crank 15 is in the initial extreme position shown in Fig. 1, a switch point does not fit up against 20 its adjoining rail, as it is desired it should fit, all that is necessary to do is to release the lock nuts 31 and 32, move the bolt 21 slightly in lug 15, reset the lock nuts, thus quickly and easily effecting the desired adjustment, so that the switch point will fit 25 up against the adjoining rail.

When it is desired to throw the switch, so that the second of the two switch points 30 engages its adjoining rail, the handle C is rotated to move crank E in its semi-circular path shown by the arrow in Fig. 2. It will be noted in reference to Fig. 2, that the crank E will move a certain distance before it strikes the face of the head 24, which has 35 an adjustable connection with slide bar 14, similar to the above described adjustable connection of head 23 with slide bar 14.

The crank E continues in contact with the 40 face of head 24, until it reaches its other extreme position shown at 33 in Fig. 2, when the switch bar mechanism as a whole will have moved toward the right the desired distance to cause the second switch point to fit up against its adjoining rail.

45 By means of this construction, accurate and quick and easy adjustment of head 24 by bolt 22 and lock nuts 31 and 32 can be effected as above described in connection with the adjustment of head 23 by bolt 21 and lock nuts 31 and 32. And another important feature of this arrangement is that the adjustment of head 23 is entirely independent of and does not affect the adjustment of head 24, so that either or both adjustments may be made at any time.

Also by my improved construction toggle 60 action of other stands is eliminated and the movement of the switch points is effected by a straight line movement of the slide bar 14 through mechanism accessible yet protected within the switch stand casing.

While I have shown and described and 65 have pointed out in the annexed claims certain novel features of the invention, it will be understood that various omissions, sub-

stitutions and changes in the forms and details of the device illustrated and in its operation may be made by those skilled in the art without departing from the spirit of the invention.

70

Having described my invention, I claim:

1. The combination with a switch stand, having a rotatable spindle provided with a crank, of a switch bar secured to the switch points, an adjusting mechanism for the 75 switch points comprising a plurality of heads positioned to be engaged alternately by the crank, each head being independently adjustable with relation to the switch bar, and means for securing each of said heads in adjusted position, said means comprising a plate secured to said bar, a lug mounted on said plate, an adjustable spacing rod supported by said lug, and secured to said head.

80

2. The combination with a switch stand, having a rotatable spindle provided with a crank, of a switch bar secured to the switch points, an adjusting mechanism for the switch points comprising a plurality of heads positioned to engage alternately with 85 the crank, each head being independently adjustable with relation to the switch bar, and means for securing each of said heads in adjusted position, said means comprising a spacing rod adjustably supported on said 90 bar, and secured to said head.

95

3. The combination with a switch stand having a rotatable spindle provided with a crank, of a switch bar secured to the switch points, an adjusting mechanism for the 100 switch points comprising an adjustable head engageable by said crank and slidably on said bar and lugs for guiding said head on said bar, and means for securing said head in adjusted position.

105

4. The combination with a switch stand having a rotatable spindle provided with a crank, of a switch bar secured to the switch points, an adjusting mechanism for the switch points comprising a spacing rod 110 and a head carried by said rod.

5. The combination with a switch stand, having a rotatable spindle provided with a crank, of a switch bar secured to the switch points, an adjusting mechanism for the 115 switch points, comprising a spacing rod maintained at all times in substantially parallel relation to said bar, and means on said rod engaged by the crank.

6. The combination with a switch stand, of a slide bar movable in a straight line direction, means on the switch stand including a crank for imparting such straight line movement to said bar, a spacing rod and adjusting means connected with the spacing 125 rod comprising a head member engageable by said crank and secured to the spacing rod, said spacing rod being supported by a lug operatively secured to said bar.

7. The combination with a switch stand 130

having a rotatable spindle provided with a crank, a switch bar secured to the switch points, an adjusting mechanism for the switch points comprising a plurality of heads positioned to engage alternately with the crank, each head being independently adjustable with relation to the switch bar, and means for securing said heads in adjusted position.

10. 8. The combination with a switch stand, having a rotatable spindle provided with a crank, of a switch bar secured to the switch points, an adjusting mechanism for the switch points, comprising a plate secured to said bar, a lug rigidly mounted on said plate, a spacing rod supported by said lug and a head carried by said rod.

9. The combination with a switch stand, having a rotatable spindle provided with a crank, of a switch bar secured to the switch points, an adjusting mechanism for the switch points, comprising an adjustable head engageable by said crank and means for securing said head in adjusted position.

25. 10. The combination with a switch stand, having a rotatable spindle provided with a crank, of a switch bar secured to the switch points, an adjusting mechanism for the switch points comprising an adjustable head engageable by said crank and slidable on said bar and means for securing said head in adjusted position.

11. The combination with a switch stand, of a slide bar movable in a straight line direction, means on the switch stand including a crank for imparting such straight line movement to said bar, a spacing rod and adjusting means connected with the spacing rod, comprising a head member engageable by said crank and carried by said rod and slidable on said bar.

12. The combination with a switch stand, of a slide bar movable in a straight line direction, means on the switch stand includ-

ing a crank for imparting such straight line movement to said bar, a spacing rod and adjusting means connected with the spacing rod, comprising a head member adjustably supported by said spacing rod and slidable on said bar.

5. 13. The combination with a switch stand, of a slide bar movable in a straight line direction, means on the switch stand including a crank for imparting such straight line movement to said bar, a plurality of spacing rods and adjusting means connected with said spacing rods, comprising a plurality of head members to be alternately engaged by said crank and carried by said rods and adjustable on said bar.

20. 14. The combination with a switch stand, of a slide bar movable in a straight line direction, means on the switch stand including a crank for imparting such straight line movement to said bar, a plurality of spacing rods and adjusting means connected with said spacing rods, comprising a plurality of head members supported by said rods and adjustable on said bar.

25. 15. A switch actuating mechanism comprising a bar rigidly secured to the switch points, a plurality of spaced plates secured to the bar, each having a projecting lug, a spacing bolt adjustable in each lug, a head carried on each of said bolts and means between said heads adapted to engage them alternately to reciprocate said bar.

30. 16. A switch actuating mechanism comprising a bar connected to the switch points, a plurality of spaced lugs secured to said bar, a spacing bolt adjustable in each lug, a head carried on each of said bolts, and a crank between said heads adapted to engage them alternately to reciprocate said bar.

In testimony whereof I have hereunto set my hand.

PAUL HOFFMAN.
